ATTORNEY

UNITED STATES PATENT OFFICE.

FRANK K. ANDREWS, OF BISHOP, CALIFORNIA

DISPLAY-BOX.

965,680.

Specification of Letters Patent. Patented July 26, 1910.

Application filed February 25, 1909. Serial No. 479,861.

To all whom it may concern:

Be it known that I, FRANK K. ANDREWS, citizen of the United States, residing at Bishop, in the county of Inyo and State of California, have invented new and useful Improvements in Display-Boxes, of which the following is a specification.

This invention relates to stock containers, and particularly to display boxes.

10 It is a purpose of my invention to provide a cheap, simple and practical device, whereby a clerk or store-keeper may promptly and accurately select from the stock on the shelves, the article desired; it 15 further provides means which will permit sufficient light to enter a box to enable the contents to be plainly discernible and displayed, so that a customer may, while waiting for the services of a clerk, glance over 20 the goods until he has discovered the material or article wanted; in this way assisting the clerk.

Particularly, my invention relates to a device which may be quickly and easily applied to stock boxes, such as contain hats, 25 shoes, shirts, hose, or other articles.

The invention consists of the parts and the construction and combination of parts as hereinafter more fully described and 30 claimed, having reference to the accompanying drawings, in which—

Figure 1 is a front view, slightly in perspective, of the improved box. Fig. 2 is a vertical section of same. Fig. 3 shows 35 the device used as a cutter. Fig. 4 illustrates the blank of the frame. Fig. 5 is a cross-section of the device.

In the embodiment of my invention, I employ a box 2, such as is utilized by 40 merchants to hold hats, shoes, ties, etc.

At present when a clerk wishes to select from the shelves the goods to be shown the customer, he has to raise the cover of each box until he finds the one desired, often requiring the use of a ladder to reach the higher shelves. To obviate this great labor, and to save time, I provide each box with an opening 3 of any desired shape or size, and over the opening is secured a piece of 45 transparent colorless material 4, such as glass, celluloid, or any substance which will serve the purpose. In order that the thus lighted display box may be made so cheaply that the manufacturer or distributor may 50 be able to furnish them free to his customers, as an inducement against his competitors,

and as an advertisement, it is necessary that the means for securing the transparency 4 be very simple, inexpensive, and attachable to any boxes which have been previously 50 manufactured. This is accomplished by the use of a window-frame 5 made of any desirable substance and in one single piece, and preferably of sheet-metal; the cut unfolded blank being shown in Fig. 4, and having 55 longitudinal panels or flanges 6 foldable inwardly and over the side edges of the transparency 4. One end of the blank has the transverse panel or flange 7 foldable to form one end stop to the transparency 4. The 60 opposite end of the blank has two opposed transverse flaps 8 struck up from it which are adapted to receive a suitably inscribed stock-card 9 which may be quickly and readily inserted between the adjacent beads and 65 is changeable at will by the merchant. Also, the inner flap when bent up, as in Fig. 2, forms a stop to hold the transparency 4 in place after the same has been slipped into 70 the guides formed by the flanges 6. The 75 frame made from this blank is formed with a suitable window opening, over which the transparency 4 fits, and the inner edges of the frame have tongues 10 adapted to be folded back first at right angles to the plane 80 of the frame or transparency holder, so as to cut out the opening 3 in the box in the first instance, and then to be folded flat over the edges of the opening inside the box to hold the attachment securely to the box. 85 Additional foldable intermediate fasteners 90 11 may be provided.

Where the holders are to be attached to boxes already in use, the tangs 10 which are approximately triangular and have their 95 apices close to the ends of the holder so that when these tangs are bent backwardly at an angle of about 90° to the plane of the holder, one or the other pair of them presents a cutting edge which may be utilized, as 100 shown in Fig. 3, to cut the opening 3 in the box, and forming parallel slots just the width of the window opening in the holder; the operator simply pushing two of the tangs through the box and then making a 105 drawing cut of the right length, and afterward cutting the ends of the slit cardboard.

By first placing the holder upon the box at the position it is desired to secure the window, and lightly pressing down on the holder, the points of the cutters 10 will make an incision or mark; and then lifting one 110

end of the holder and depressing the cutters on the other end until they sever and enter the material of the box, whereupon by drawing the holder firmly forward until the 5 mark 13, Fig. 3, is reached, a pair of parallel cuts are made just the right length and distance apart. The tangs 10 may then be used to make the cross-cut at the ends of the slots, thereby forming an opening in the box just 10 the area of that within the frame. This having been completed, it is only necessary to place the back of the holder against the box and close to the edges of the opening 3, so that the several fasteners 10 and 11 may be 15 bent by hand to fold over and clamp the contiguous edges of the box, manifestly forming a practically dust- and insert-proof joint between the frame and the box.

By this device much valuable time is 20 saved; the stock is not shop-worn by constant handling; a customer is frequently able to select the article he desires, and without taking the cover off of the box; all of the stock is constantly on display, but protected 25 from dust and injury; and by having a convenient, removable stock-card 9 the taking of an inventory of stock is greatly facilitated.

Having thus described my invention, 30 what I claim and desire to secure by Letters Patent is—

1. A display attachment for stock boxes, comprising a metallic frame having an opening and provided with inwardly extending, bendable clamping tangs and also 35 having marking blades disposed adjacent the ends of the opening and bent, at approximately right angles, backwardly from the frame, the points of the blades indicating

the corners of the opening when pressed into 40 the material of the stock-box.

2. The combination of a stock box and a display frame having an opening and being provided with rearwardly bent marking and cutting blades at the extremities of the opening, said blades adaptable to be pressed into 45 the material of the stock box and mark the same for cutting an opening of similar form to the opening of the frame.

3. The combination with a stock box, of a 50 display attachment therefor, said attachment embodying a frame formed of sheet metal and fashioned with an opening, bendable retaining tangs extending from the frame transversely across the opening, and 55 marking and cutting blades adapted to be pressed into the material of the box to mark and cut in the same an opening of similar form to that of the frame.

4. A blank for display attachments for 60 stock-boxes, said blank being formed of sheet-metal and having an opening, bendable retaining tangs extending across the opening, cutting and marking blades having 65 short sides parallel with and adjacent the ends of the opening and long sides or edges intersecting said short sides in an acute angle and adapted when bent back at right angles to the frame to present cutting edges whereby the material of the box may be marked 70 and cut.

In testimony whereof I have hereunto set my hand in presence of two subscribing witnesses.

FRANK K. ANDREWS.
